SANDER VALVE

Charles A. Campbell, Watertown, N. Y., assignor
to The New York Air Brake Company, a cor-
poration of New Jersey

Application March 19, 1934, Serial No. 716,386

20 Claims. (CL 291—15)

This invention relates to track sanders, and particularly to valve mechanism for controlling the supply of air to pneumatically actuated sand traps.

One object of the invention is to provide for sustained sanding over a definite time period. Another object is to ensure this type of operation where the motive air for sanding is drawn directly from the main reservoir or similar source, and not from a secondary reservoir or measuring chamber. This is conducive to more evenly sustained operation.

Another object of the invention is to secure automatic sanding by the motion of an automatic or other application valve to emergency application position, and to terminate this sanding after a definite time interval even though the application valve remains in emergency application position.

Another object is to provide simple means associated with the timed sander to permit sanding at will, such means preferably being rendered inoperative when timed sanding is in progress.

The preferred embodiment of the invention is illustrated in the accompanying drawing, in which the single figure is a view partly in section and partly in elevation, of the sander valve mechanism and associated parts.

In the drawing, 2 is a pipe leading from the main reservoir or other source of compressed air. A branch of pipe 2 leads to the chamber 3 in body 4 of the sander relay valve. In chamber 3 is mounted a ported bushing 5 having a seat rim 6, on which a rubber poppet valve 7 seats.

The bushing 5 is retained in place and chamber 3 is sealed by a removable closure cap 8, which also serves as a seat for the coil compression spring 9.

When valve 7 is unseated main reservoir air flows to passage 11 which leads to the sand traps. These may be of any suitable type, but preferably are of the known type having a cleaning jet and a sanding jet with automatic valve means for delivering an initial momentary blast to the cleaning jet as the sanding jet goes into action.

To open valve 7, a pressure motor is incorporated in body 4. This comprises a diaphragm 12 clamped at its periphery to body 4 by a cap 13, there being a motor chamber 14 within cap 13 in which fluid pressure reacts on the lower face of the diaphragm. The space above the upper face is vented to atmosphere at 15. A thrust rod 16 is guided in a guideway in body 4

and has a thrust disk 17 in contact with the upper face of the diaphragm.

When diaphragm 12 is flexed upward valve 7 is unseated and main reservoir air flows directly to the sand traps and operates them in the usual manner.

A passage 18 and pipe 19 connect chamber 14 with passage 21 in body 22 of the controlling valve.

Body 22 is provided with attaching lugs 23 and encloses two axially aligned cylinders 24 and 25 connected by a coaxial bore 26 which serves as a chamber for a balanced piston valve of the inside cutoff type. This valve comprises two heads 27 and 28 and a connecting reduced portion 29. The heads 27 and 28 are freely slidable in bore 26 and are provided with suitable leakage resistance means, such as the grooves shown.

Attached to the end of head 27 is a piston 31 working in cylinder 24 and attached to the end of head 28 is a similar piston 32 working in cylinder 25. Cylinder 25 has a bypass groove 33 intended to equalize the pressures on the two faces of the piston 32 as the piston moves to the left and slightly before head 28 blanks port 47, hereinafter described. The two pistons are cup-shaped and present outwardly extending flanges which seat on gaskets to seal the respective pistons when at their respective outer limits of motion.

The end of cylinder 24 is closed by a cap 34, with gasket 35, which not only seals the cap, but also serves as a seat for the rim of piston 31. Slidably in cap 34 is a push button element 36 which, when pushed clear in, shifts the valve 35 and piston assembly at least far enough to cause head 28 to uncover port 47.

Such motion is resisted by a coil compression spring 37 reacting between piston 32 and cap 38. Cap 38 is vented to atmosphere at 39 but positions a gasket 41 against which the rim of piston 32 seals when at its outer limit of motion. The inner end of cylinder 24 is vented to atmosphere at 42.

The main reservoir pipe 2, leads to a port 43 which is fully exposed by head 27 when in its left-hand position. At such time the clearance around the reduced portion 29 of the valve, offers connection to port 44 and thence by way of pipe 45 to a closed volume or timing chamber 46. Port 44 always communicates with the space surrounding reduced portion 29.

When the valve has been forced to the right far enough for head 27 to close port 43, head 28 starts to expose port 47 which leads to the space at the

left of piston 32. The admission of air from chamber 46 against piston 32 causes the piston to move its full stroke to the right, in which limiting position head 28 exposes port 48, leading by way of passage 21, pipe 19, and passage 18 to chamber 14 of the sander valve motor.

Passage 21 is vented to atmosphere through a removable choke 49. The relation of the size of the choke 49 to the volume of the timing chamber 46 determines the duration of timed sanding.

The space to the left of piston 31 is connected by passage 51 and pipe 52 to the body of a brake application valve 53. This application valve 53 may be of the manually actuated type, but is here assumed to be of the automatic type, operable by the functioning of a deadman valve. So far as the present invention is concerned it is essential merely that the application valve have an emergency position, in which position it admits air under pressure into pipe 52.

When head 27 exposes main reservoir port 43, this communicates with a port 54, but this port is blanked by head 27 in the right hand position of the valve. Port 54 leads to the seat of a balanced piston valve 55, the lower head of which normally blanks port 54. When valve 55 is forced downward a reduced portion 56 of the valve connects port 54 and port 57 which communicates with a branch of passage 21. Button 58 limits the depression of valve 55 and the coil compression spring 59 restores the valve to closed position when released. A vented spring seat 61 encloses and sustains the spring.

35 Operation

Manual sanding without timing.—If button 58 be depressed main reservoir air flows via 2, 43, 54, 56, 57, 21, 18, 18 to chamber 14, forcing up diaphragm 12 and unseating valve 7. When the button is released spring 59 restores valve 55, choke 48 relieves the pressure on diaphragm 12, and valve 7 closes.

Manual sanding with timing.—The operator presses button 36 inward partially shifting the piston and valve assembly. As soon as head 28 uncovers port 47 air pressure admitted against piston 32 snaps the piston to the right against gasket 41. Button 36 remains in. Pressures in chambers 46, 14 and cylinder 25 to the left of piston 32, equalize and diaphragm 12 rises and holds valve 7 open.

The pressure fluid in the spaces just defined bleeds slowly away through choke 49 and after a period dependent on the volume of chamber 46 and size of choke 49, the piston 32 will start to the left under the urge of spring 37. Shortly before head 28 closes port 47 piston 32 is bridged by bypass groove 38 which vents the pressure to the left of piston 32. Thereupon the piston and valve assembly moves rapidly to the left, restoring button 36. Until it is reset port 54 is blanked and valve 55 is rendered inoperative because deprived of an air supply.

The sanding period may readily be given any desired duration, but 30 seconds is typical.

Timed sanding in emergency.—If the brake application valve is moved to emergency position motive fluid is admitted against piston 31, forcing it to the right. Sanding will occur as already described, except that so long as piston 31 is under pressure the valve cannot reset itself. Nevertheless, valve 7 will close at the end of the timing period for choke 49 dissipates the pressure in diaphragm 12 independently of the resetting of the pistons and piston valve.

An important aspect of the invention is the fact that sanding air is taken directly from the main reservoir and the timing operation does not limit the quantity nor affect the maintained pressure of the air used in the sanding operation. 5

Various possible modifications within the scope of the invention are contemplated. Pistons and diaphragms are generally interchangeable. Other yielding devices may be substituted for springs, while various valve structures may be devised to control the timing of a plurality of flows. By availing of such substitutions the actual structure may be considerably varied.

What is claimed is: —

1. In a sanding device, the combination of a main source of operating air; a normally closed valve controlling the entire flow of air from said source to a sander; means for opening said valve; and automatic means for closing said valve and thus terminating the operation of the sander 20 after a definite time interval.

2. In a sanding device, the combination of a main source of operating air; a normally closed valve controlling the entire flow of air from said source to a sander; manually set means for opening said valve; and automatic means for closing said valve and thus terminating the operation of the sander 25 after a definite time interval.

3. In a sanding device, the combination of a main source of operating air; a normally closed valve controlling the entire flow of air from said source to a sander; a motor; means set by the energization of said motor to open said valve; a brake-applying valve having an emergency position in which it energizes said motor; and automatic means for closing said valve and thus terminating the operation of the sander after a definite time interval irrespective of the state of energization of the motor. 35

4. The combination of a sander valve controlling the flow of air to a sander; a timing reservoir; an expandible chamber motor having a reversely shiftable element; a timing valve arranged to shift with said element, said timing valve having a normal position in which it establishes a charging connection for said reservoir, and an abnormal position in which it closes said connection, connects said reservoir and motor and vents motive fluid therefrom; means effective in the abnormal position of the timing valve to open the 50 sanding valve; yielding means urging the timing valve toward normal position; and means for shifting the timing valve to abnormal position. 45

5. The combination of a sander valve controlling the flow of air to a sander; a timing reservoir; an expandible chamber motor having a reversely shiftable element; a timing valve arranged to shift with said element, said timing valve having a normal position in which it establishes a charging connection for said reservoir, and an 55 abnormal position in which it closes said connection, connects said reservoir and motor and vents motive fluid therefrom; means effective in the abnormal position of the timing valve to open the sanding valve; yielding means urging the timing valve toward normal position; a pressure motor for shifting the timing valve to abnormal position; and a brake application valve having an application position in which it admits motive fluid to the last-named motor. 60

6. The combination of a sander valve controlling the flow of air to a sander; a timing reservoir; an expandible chamber motor having a reversely shiftable element; a timing valve arranged to shift with said element, said timing valve having 70

- a normal position in which it establishes a charging connection for said reservoir, and an abnormal position in which it closes said connection, connects said reservoir and motor and vents motive fluid therefrom; means effective in the abnormal position of the timing valve to open the sanding valve; yielding means urging the timing valve toward normal position; a pressure motor for shifting the timing valve to abnormal position; a 5 brake application valve having an application position in which it admits motive fluid to the last-named motor; and manually operable means for shifting said timing valve to abnormal position.
- 15 7. The combination of a sanding valve for controlling the flow of motive fluid to a sander; a timing reservoir; a motor comprising a cylinder, a piston and means for equalizing pressures on opposite sides of the piston at one end of the piston stroke; a timing valve connected to shift with said piston, said timing valve having a normal position in which said equalizing means is effective and said valve establishes a charging connection to said reservoir, and an abnormal position in which said equalizing means is ineffective and the valve closes said charging connection and directs pressure fluid from said reservoir against said piston and slowly vents said reservoir; means effective in said abnormal position of the timing 20 valve to open the sanding valve; yielding means urging the timing valve to normal position; and means for shifting the timing valve toward abnormal position.
8. The combination of a sanding valve for controlling the flow of motive fluid to a sander; a timing reservoir; a motor comprising a cylinder, a piston and means for equalizing pressures on opposite sides of the piston at one end of the piston stroke; a timing valve connected to shift with said piston, said timing valve having a normal position in which said equalizing means is effective and said valve establishes a charging connection to said reservoir, and an abnormal position in which said equalizing means is ineffective and the valve closes said charging connection and directs pressure fluid from said reservoir against said piston and slowly vents said reservoir; means effective in said abnormal position of the timing 25 valve to open the sanding valve; yielding means urging the timing valve to normal position; and means for shifting the timing valve toward abnormal position.
- 40 9. The combination of a sanding valve for controlling the flow of motive fluid to a sander; a timing reservoir; a motor comprising a cylinder, a piston and means for equalizing pressures on opposite sides of the piston at one end of the piston stroke; a timing valve connected to shift with said piston, said timing valve having a normal position in which said equalizing means is effective and said valve establishes a charging connection to said reservoir, and an abnormal position in which said equalizing means is ineffective and the valve closes said charging connection and directs pressure fluid from said reservoir against said piston and slowly vents said reservoir; means effective in said abnormal position of the timing 45 valve to open the sanding valve; yielding means urging the timing valve to normal position; a pressure motor for shifting the timing valve to abnormal position; and a brake application valve having an application position in which it admits motive fluid to the last-named motor; and means for shifting the timing valve toward abnormal position.
- 50 10. The combination of a sander valve controlling the flow of air to a sander; a timing reservoir; an expandible chamber motor having a reversely shiftable element; a timing valve arranged to shift with said element, said timing valve having a normal position in which it establishes a charging connection for said reservoir, and an abnormal position in which it closes said connection, connects said reservoir and motor and vents motor fluid therefrom; means effective in the abnormal position of the timing 55 valve to open the sanding valve; yielding means urging the timing valve toward normal position; means for shifting the timing valve to abnormal position; independent means for opening said sanding valve; and means effective in the abnormal position of the timing valve for rendering said independent means inoperative.
11. The combination of a sander valve controlling the flow of air to a sander; a timing reservoir; an expandible chamber motor having a reversely shiftable element; a timing valve arranged to shift with said element, said timing valve having a normal position in which it establishes a charging connection for said reservoir, and an abnormal position in which it closes said connection, connects said reservoir and motor and vents motor fluid therefrom; means effective in the abnormal position of the timing valve to open the sanding valve; yielding means urging the timing valve toward normal position; a pressure motor for shifting the timing valve to abnormal position; a brake application valve having an application position in which it admits motive fluid to the last-named motor; and means for shifting the timing valve toward abnormal 60 position.
12. The combination of a normally closed sander valve; a fluid pressure motor for opening the same; an admission valve for admitting motive fluid to said motor; yielding means for closing said admission valve; timing means controlling closing motion of said admission valve; a second admission valve for admitting motive fluid to said motor; means urging said second valve in a closing direction; and means associated with the first admission valve, and effective in the open position thereof for precluding the supply of motive fluid to said motor through the second admission valve.
13. The combination of a normally closed sander valve; a fluid pressure motor for opening the same; an admission valve for admitting motive fluid to said motor; yielding means for closing said admission valve; timing means controlling closing motion of said admission valve; a second admission valve for admitting motive fluid to said motor; means urging said second valve in a closing direction; normally open supervisory valve means connected in series with the second admission valve to control the flow of motive fluid; and operative connections between the first admission valve and said supervisory valve for closing the latter by the opening movement of the former.
14. The combination of a normally closed sander valve; a fluid pressure motor for opening the same; a timing reservoir; a piston; a spring urging said piston toward a normal position; a valve connected to shift as said piston shifts, said valve having a normal position in

which it establishes a charging connection to said reservoir, and an abnormal position in which it admits pressure fluid from said reservoir to said motor and against said piston in opposition to 5 said spring and gradually vents said reservoir; and means for shifting said valve to the last-named position.

15. In a sanding device, the combination of a main source of operating air; a normally closed 10 valve which when opened permits flow of air from said source to a sander; two controlling means each operable to open said valve; means for restoring each of said controlling means to inactive condition; and timing means serving to delay 15 such restoration of one of said controlling means.

16. In a sanding device, the combination of a main source of operating air; a normally closed 20 valve which when opened permits a flow of air from said source to a sander; manually operable controlling means for holding said valve open at will; a second controlling means operable to open 25 said valve; and timing means rendered active upon the opening of said valve by the second controlling means, and serving after a definite time interval to suspend the valve opening action 30 of said second controlling means.

17. In a sanding device, the combination of a main source of operating air; a normally closed 35 valve which when opened permits a flow of air from said source to a sander; manually operable controlling means for holding said valve open at will; a second controlling means operable to open 40 said valve; and timing means rendered active upon the opening of said valve by the second controlling means to retain said controlling means in active position for a definite period, and then restore it to inactive position, and serving independently of the restoration of said controlling means to suspend the valve opening action thereof.

18. In a sanding device, the combination of a main source of operating air; a normally closed

valve which when opened permits a flow of air from said source to a sander; a controlling means for said valve having a normal inactive position, and an active position in which it holds said valve open; two actuators for said controlling means, one actuator being manually operated and the other power operated; and timing means rendered active upon the opening of said valve by said controlling means to retain the controlling means in its active position and then after a definite period to permit it to return to its normal position, and serving independently of the restoration of the controlling means to normal position, to suspend the valve opening action of the controlling means.

19. The combination of a source of fluid pressure; a normally closed valve controlling the flow of pressure fluid from said source to a sander; timing mechanism arranged to be put into action to perform an operative cycle in which it opens 20 said valve and then after a definite time interval closes the same; a brake valve; and two means selectively operable to put said timing mechanism into action, one of said two means being rendered active by said brake valve and the other being 25 capable of manual actuation independently of the brake valve.

20. The combination of a source of fluid pressure; a normally closed valve controlling the flow 30 of pressure fluid from said source to a sander; timing mechanism arranged to be put into action to perform an operative cycle in which it opens said valve and then after a definite time interval closes the same; a brake valve; two means selectively operable to put said timing mechanism 35 into action, one of said two means being rendered active by said brake valve and the other being capable of manual actuation independently of the brake valve; and manually operable means for opening said normally closed valve and holding it open at will.

CHARLES A. CAMPBELL.
